(57) **CLAIM**

The ornamental design for a dual-layered glove, as shown and described.

DESCRIPTION

FIG. 1 is a front elevational view of a dual-layered glove showing my new design;

FIG. 2 is a rear elevational view thereof;

FIG. 3 is a side view, taken from the left side of FIG. 1; and, FIG. 4 is a side view, taken from the right side of FIG. 1. The fragmentary crosshatch pattern shown in the drawing is understood to represent fabric and is repeated uniformly throughout the areas shown.
